UNITED STATES PATENT OFFICE.

SAMUEL ROBINSON RIDGWAY, OF BIRMINGHAM, ENGLAND, ASSIGNOR OF ONE-THIRD TO FREDERICK JOHN RIDGWAY AND ONE-THIRD TO COLIN MOSLEY BRUNT, BOTH OF STOKE-UPON-TRENT, ENGLAND.

SPRING-FORK FOR CYCLES AND MOTOR-CYCLES.

1,108,932.

Specification of Letters Patent.

Patented Sept. 1, 1914.

Application filed November 23, 1912. Serial No. 733,141.

To all whom it may concern:

Be it known that I, SAMUEL ROBINSON RIDGWAY, subject of Great Britain, residing at Birmingham, in the county of Warwick, England, have invented new and useful Improvements in or Relating to Spring-Forks for Cycles and Motor-Cycles, of which the following is a specification.

This invention has reference to spring forks for the steering heads of cycles and motorcycles and more particularly to that type in which the fork is pivotally connected to the said head by two pairs of parallel links or levers, and in which the links of the lower pair are pivoted intermediately to their ends to the fork, their rear ends being jointed to the lower end of the steering head while their opposite free ends are directed forwardly and if necessary upwardly and carry an abutment for a spring or springs which may be either arranged parallel with or at right angles to the steering head and is or are adapted to cushion or control the movement of the fork relatively to the said head.

The primary object of the present invention is to provide a spring fork of the type herein-before referred to which while being equally as strong and efficient for its purposes is characterized by a less number of parts and is consequently of a lighter and cheaper construction than hitherto.

The invention consists in the employment in place of each of the two pairs of parallel links or levers aforesaid of means comprising a single unit which is rotatably carried by the fork and hinged to the steering head. Said means may conveniently consist of a yoke or stirrup comprising a transverse tubular member supported rotatably on a pin carried by said fork, a pair of parallel members or a single bifurcated central member extending rearwardly from said transverse member and adapted to be pivoted by their or its free ends to the upper and lower parts of the steering head, the yoke which is pivoted to the lower part of the said head being also provided with a pair of parallel members or a central stem extending forwardly and adapted to form or carry an abutment for a spring or springs arranged between the same and a fixed abutment on the fork. This yoke may take various shapes but in each case is always in one piece and

may be formed by a stamping or drop forging process.

In the accompanying drawings, Figures 1 and 2 are side and front elevations respectively of a spring fork constructed according to this invention. Fig. 3 is a transverse sectional view of the same on the line *a*—*b*, Fig. 1. Fig. 4 is a view similar to Fig. 1 of an alternative construction. Fig. 5 is a sectional view of the same on the line *c*—*d*, Fig. 4. Fig. 6 is a plan representing the attachment of the upper part of the fork to the head. Figs. 7 and 8 each comprise plan and side elevational views of alternative constructions of the yoke. Fig. 9 is a plan view of another modification.

Throughout the drawings like parts are designated by similar reference characters.

Referring to the drawings, 2 represents the fork which is of girder construction and may be made in halves, 3 the steering head to which the fork is pivotally attached and 4 is the spring or springs whereby relative movement between the said head and the fork is cushioned or controlled.

In the construction shown in Figs. 1, 2 and 3 the yoke as applied in place of the lower pair of levers at present in use comprises a transverse tubular member 5 which is adapted to be supported rotatably upon a pin 6 carried horizontally by the fork sides. Projecting forwardly from this member is a centrally arranged stem 7 the free end of which is turned upward so that as the yoke is moved about the pivot pin 6 as the result of relative movement between the head and the fork the end of the said forward stem would move to compress the spring 4 in a direction at right angles to the steering head. The free extremity of this forward stem may either be formed with or carry a cup 8 to form an abutment for one end of the spring 4 and in the latter case the cup would for preference be hinged to the stem on a horizontal pin 9 as shown. The other end of the spring abuts against the cup 10 carried by the fork. The rear part of the yoke comprises in this construction a pair of parallel arms 11 or a bifurcated central stem the free ends of which are pivoted to lugs 12 on the lower end of the steering head or column 3 which is mounted so as to be free to rotate on ball bearings, in the tubular head 13 of

the frame in the well known manner. As regards the upper end of the fork the parallel links by which the latter is usually pivoted to the top of the steering head are replaced by a single yoke, see Figs. 1, 2 and 4, and more particularly Fig. 6. This yoke 5 comprises a transverse tubular member 5 which is mounted rotatably on a pin 6 carried horizontally between the upper ends of the fork 2, and a pair of rearwardly directed arms 11 or a bifurcated central stem which in each case form or forms an integral part of the transverse member 5 and have or has their or its free ends jointed to lugs 12 on the top of the steering head 3. One advantage accruing from this arrangement is that it enables the fork to be made in halves.

Where as in Figs. 4 and 5 the spring 4 is arranged with its axis parallel or approximately parallel with the steering head the forwardly directed stem 7 of the yoke would project at right angles to the said head and carry a pivoted cup 8 forming the lower abutment for the spring. In this construction the abutment 10 for the upper end of the spring is carried between the stays 14 which form part of the fork.

As already stated the yoke may take various forms, for example as shown in Fig. 9, the transverse tubular member 5 may have projecting from each side of it a centrally arranged stem 7, 15 having bifurcated free ends. The bifurcated stem 15 at the rearward side is adapted to be pivoted by each of its limbs or arms 16 to the lugs 12 on the lower end of the steering head while the bifurcated ends 17 of the forwardly directed stem are adapted to carry a cup 8 or its equivalent for the reception of one end of the spring or springs.

In the alternative arrangements shown in Figs. 7 and 8 the rearwardly and forwardly directed stems may be replaced by a pair of parallel arms 11, 18 projecting rearwardly and forwardly from and integral with the transverse member 5. Any desired combination of these two arrangements may also be employed as circumstances permit. Fig. 8 represents similar constructions to those in Fig. 7 as applied where the spring 4 is arranged with its axis parallel or approximately with the steering head. Any desired combination of these two constructions may be likewise employed.

From the foregoing it will be seen that by reason of the reduction in the number of parts constituting the complete fork the latter may be made more suitable than hitherto for motorcycles of the light weight class 60 without impairing its strength and antivibratory properties.

What I claim and desire to secure by Letters Patent of the United States is—

1. A spring fork for motorcycles and the like comprising in combination, a steering head, a pair of fork members flexibly connected with the upper part of said head, means consisting of a single unit pivotally mounted between said fork members and hinged to the lower part of said steering head, a fixed abutment on the fork members, and a spring or springs arranged between said abutment and said unit substantially as set forth.

2. A spring fork for motorcycles and the like comprising in combination a steering head, a pair of fork members flexibly connected at their upper ends to the upper part of said head, a yoke pivotally mounted between said fork members and having one end hinged to the lower part of the said head, a fixed abutment on the fork members, and a spring or springs arranged between said abutment and the other end of the said yoke substantially as set forth.

3. A spring fork for motor-cycles and the like comprising in combination a steering head, a pair of fork members flexibly connected at the upper ends with said head, a yoke comprising a transverse tubular member supported by and between said fork members, a single bifurcated member projecting rearwardly therefrom and hinged to said head and a single bifurcated member projecting forwardly from said tubular member, a fixed abutment carried by said fork members and a spring or springs arranged between said abutment and said forwardly projecting bifurcated member and adapted to be compressed by the said forwardly bifurcated member of the yoke, substantially as herein set forth.

In testimony whereof I have signed my name to this specification in the presence of 105 two subscribing witnesses.

SAMUEL ROBINSON RIDGWAY.
